CLAIM

The ornamental design for a pharmaceutical check box, as shown.

DESCRIPTION

FIG. 1 is a perspective view of a pharmaceutical check box taken from the left-hand front side, illustrating my new design;

FIG. 2 is a perspective view looking toward the rear right-hand side of the pharmaceutical check box constructed in accordance with my new design, and

FIG. 3 is a perspective view looking toward the right front underneath side of the pharmaceutical check box illustrating my new design.

*Fig. 1.**Fig. 2.**Fig. 3.*
